UNITED STATES PATENT OFFICE.

PATRICK FITZGIBBONS, OF OSWEGO, NEW YORK.

STEAM-BOILER.

SPECIFICATION forming part of Letters Patent No. 247,551, dated September 27, 1881.

Application filed July 18, 1881. (No model.)

To all whom it may concern:

Be it known that I, PATRICK FITZGIBBONS, of Oswego, in the county of Oswego, in the State of New York, have invented new and useful 5 Improvements in Steam-Boilers, of which the following, taken in connection with the accompanying drawings, is a full, clear, and exact description.

This invention relates to a novel construction of a return-flue boiler and the connection of same with the furnace thereof, designed more particularly for the use of straw and other light combustibles as fuel for generating steam, and in which are combined structural stability 15 with superior facility for regulating the heat of the furnace and the application of said heat to the boiler, and also with greater safety against communicating fire to surrounding objects.

20 The invention is fully illustrated in the annexed drawings, wherein Figure 1 is a longitudinal section of my improved steam-boiler; and Figs. 2, 3, and 4 are transverse sections on lines $x x$, $y y$, and $z z$, respectively.

25 Similar letters of reference indicate corresponding parts.

B denotes the boiler proper, made cylindrical throughout its length, and having under its front end the furnace or fire-box F, which is 30 surrounded by a water-jacket, e, connected with the boiler, and communicating with the water-space thereof.

The furnace is made in one complete shell, having its upper corners curved, as shown at 35 a , and its crown-sheet b made with a segmental downward deflection in the form of an arc described from the axial center of the boiler, and with the same radius as that of the boiler-shell. Said crown-sheet is made to serve as the bottom of the boiler, the main portion of the 40 boiler-shell over the furnace being segmental in form and riveted at its longitudinal edges to the top of the crown-sheet, thus maintaining the cylindrical form of the boiler throughout its length. The furnace extends part way the 45 length of the boiler, and its rear end communicates with large flues A, which are extended through the rear portion of the boiler to the usual combustion-chamber, C, on the rear end,

from whence the products of combustion return to the smoke-box D and stack S, at the front end of the boiler, by flues f , extended through the boiler. The furnace is also made to communicate direct with the smoke-box D by large flues A', which are extended from the rear end of the furnace through the forward portion of the boiler, as shown in Fig. 1 of the drawings.

In order to obtain the requisite access to the inner ends of the flues A A' for properly fitting, upsetting, and repairing the same, when necessary, I connect said ends with a vertical extension of the rear end of the furnace, projecting part way into the boiler, said extension being made by an opening, E, of the requisite size, in the bottom of the boiler-shell, through which opening the upper portion of the inner back sheet of the furnace is extended, the protruding portion of said sheet forming a segmental flue-sheet, c, which extends across the bottom of the boiler and has connected thereto the forward end of the flues A. A similar segmental flue-sheet, c', is secured to the interior bottom of the boiler, at the opposite side of the aforesaid opening, and has secured to it the rear end of the flues A'. A crown-sheet, d, extended across the opening and secured to the free edges of the two flue-sheets c c' and to the side plate of the furnace, completes the vertical extension of the rear end of the furnace. The ends of the flues A' are provided with a suitable valve or damper, v, by which the direct draft through said flues can be regulated.

The described arrangement of the short and direct return-flues A', with their dampers v, is deemed an essential improvement in straw-burning return-flue boilers, in that they afford a convenient and effective means of quickly increasing the draft, when desired, and as quickly checking the draft in case the stack throws sparks, endangering surrounding objects.

Having described my invention, what I claim as new is—

1. A return-flue boiler having at the front end a subjacent fire-box communicating with a combustion-chamber on the rear end of the boiler by flues extended through the rear por-

- tion of the boiler, a smoke-box and stack on the front end of the boiler, communicating with the rear combustion-chamber by flues extended through the length of the boiler, and communicating, also, with the fire-box by flues extended through the forward portion of the boiler directly to the fire-box, substantially as shown and set forth.
2. The combination of the boiler B, provided with the return-flues *ff*, combustion-chamber C, and smoke-box D, the furnace F, arranged underneath the boiler and extended part way the length thereof, and having at its rear end a vertical extension projecting into the boiler, the flues A A', extended from said extension

respectively rearward to the combustion-chamber C and forward to the smoke-box D, and valve or damper *v*, all combined as described and shown.

In testimony whereof I have hereunto signed my name and affixed my seal, in the presence of two attesting witnesses, at Oswego, in the county of Oswego, in the State of New York, this 5th day of July, 1881.

PATRICK FITZGIBBONS. [L. S.]
